(57) **CLAIM**

The ornamental design for a handle for a micro-needle device, as shown and described.

DESCRIPTION

FIG. 1 is a top perspective view of a handle for a micro-needle device;

FIG. 2 is a left side elevational view of the handle for a micro-needle device of FIG. 1; the right side elevational view being a mirror image thereof;

FIG. 3 is a front elevational view of the handle for a micro-needle device of FIG. 1;

FIG. 4 is a rear elevational view of the handle for a micro-needle device of FIG. 1;

FIG. 5 is a top plan view of the handle for a micro-needle device of FIG. 1; and,

FIG. 6 is a bottom plan view of the handle for a micro-needle device of FIG. 1.

The portions of the figures depicted in broken lines are for illustrative purposes only and form no part of the claimed design.
